LIP STICK HOLDER

John W. Fitz Gerald, Milwaukee, Wis., assignor
to Briggs & Stratton Corporation, Milwaukee,
Wis., a corporation of Delaware

Application November 9, 1931, Serial No. 573,953

6 Claims. (Cl. 206—56)

This invention relates to lipstick holders and more particularly to a lipstick holder adapted to be actuated by a button on the exterior of the holder, the action of which is entirely automatic to both raise the cover and expel the lipstick.

It is a further object of the present invention to generally improve the construction of lipstick holders and reduce the handling of the lipstick to a minimum, and other objects will appear in the course of the following description.

A structure embodying the invention is illustrated in the accompanying drawings and will be hereinafter fully described, the invention residing in certain novel features which will be particularly pointed out in the appended claims.

In the drawings:

Figure 1 is a side view of the lipstick holder showing the actuating button, parts thereof being broken away to show the construction of the interior;

Figure 2 is a cross section on the line 2—2 of Fig. 1, looking in the direction of the arrows, parts thereof being cut away to more clearly illustrate certain other parts;

Figure 3 is a view similar to Fig. 2, but showing the protective sleeve in projected position and the lipstick in retracted position;

Figure 4 is a view similar to Fig. 2, showing both the lipstick and the cap actuating sleeve in projected position;

Figure 5 is a cross section on the line 5—5 of Fig. 2, looking in the direction of the arrows;

Figure 6 is a cross section on the line 6—6 of Fig. 3, looking in the direction of the arrows;

Figure 7 is a cross section on the line 7—7 of Fig. 3, looking in the direction of the arrows;

Figure 8 is a cross section on the line 8—8 of Fig. 4, looking in the direction of the arrows;

Figure 9 is a perspective view of the outer casing of the lipstick holder showing the cover in place;

Figure 10 is a perspective view of the cap raising sleeve, a part thereof being broken away to more clearly illustrate the construction;

Figure 11 is a perspective view of the lipstick retainer.

Referring to the accompanying drawings in which like numerals indicate like parts throughout the several views, the lipstick holder has an outer casing or container 15 having a closed inner end and an open outer end and provided with a longitudinal slot 16 running axially of the casing, and a peripheral bead 18 at the outer edge of the casing and running throughout the circumference parallel to the outer edge, the

interior of the bead forming a groove 20 on the inside of the container 15.

In the following description, when the term inner or outer end of any member is referred to, it shall be used to designate that end when in normal position in the casing 15 adjacent the inner closed end or the outer open end of the casing.

A cap 22 comprises a closure having an in-turned peripheral edge 23, one part of the edge 10 23 being extended and bent back into the cap as shown at 25 to provide a guide which enables a cap raising member to lift the cap off the open end of the casing. The cap is hingedly connected to an annular spring 27 and has a helical 15 spring 28 constantly urging the cap into closed position on the casing 15.

Both the container 15 and the cap 22 may be plated with gold, silver, chromium or like lustrous material or may be formed of enamel to 20 increase the attractiveness of the article.

A cover raising sleeve, generally designated 30, is mounted for axial movement in the casing 15 and comprises a cylindrical member rolled from a piece of resilient sheet metal with the 25 ends of the rolled portion 31 and 32 spaced slightly apart and adapted to permit radial expansion of the member 30 for a purpose herein-after set forth. The outer portion of the sleeve 30 is cut away for part of the circumference as 30 shown at 35, the cut away portion 35 fitting within the container 15 adjacent the hinge to preclude the possibility of the sleeve 30 catching beneath the hinge 27 or the spring 28 and preventing movement of the sleeve 30 outwardly. 35

A slot 38 is provided in the sleeve running axially therein at a point diametrically opposite the ends 31 and 32. The slot 38 is adapted to register with the slot 16 in the outer shell 15 but may be considerably shorter due to the movement of the sleeve 30.

A circumferential slot 40 is likewise provided in the wall of the sleeve 30 spaced from the outer end thereof which is adapted to be engaged by an end 42 of the spring 27 to yieldably prevent movement of the cylindrical member 30 therewith when the end 42 is engaged with the slot 40. The slot 40 is spaced in from the outer edge of the sleeve 30 to stop the movement of the sleeve at a point when the 50 cover 22 is fully open.

A lipstick retainer, generally designated 45, comprises a cylindrical member 46 having an instruck bead 48 adjacent the outer edge thereof and provided with a plurality of tongs or 55

5 fingers 50 having outstruck beads 52 on the inner edge thereof. A port 54 receives a pin 57 which passes through the aligned slots 16 and 38 and is fastened in the port 54 for actuating the lipstick retainer 45 and the sleeve 30.

10 The device is assembled by hingedly mounting the cover 22 from the circumferential spring member 27 and mounting the lipstick retainer 45 within the sleeve 30 with the port 54 aligned with the slot 38 and with the beads 52 beneath the lower edge of the cylindrical sleeve 30. The assembled members 30 and 45 may then be readily inserted into the interior of the casing 15 in such a position that the slot is aligned with the slot 16 in the casing 15. The pin 57 may then be inserted through the aligned slots 16 and 38 and into the port 54 where it may be retained by any suitable method, such for example, as riveting. The pin may then be used 20 to retract both members 30 and 45 into the lower part of the lipstick holder and the cover closed automatically as the sleeve 30 drops below the level of the cover.

25 A lipstick 60 may then be inserted in the retainer 45 and held therein by the bead 48.

Operation

30 The operation of the lipstick holder is best seen by referring to the various figures.

35 Referring first to Figs. 2 and 7, it will be seen that with the lipstick in retracted position, and the cover closed over the entire container, the beads 52 lie below the inner end of the shell 30 and that the outer end of the shell 30 projects beyond the circumferential spring 27. Propelling the button 57 towards the cap 22 causes the beads 52 to grip the end of the sleeve 30 and expel both the sleeve 30 and the lipstick retainer 45 together with the lipstick 60, the sleeve 30 engaging the member 25 on the cover 22 to open the cover in advance of the sleeve.

40 When the sleeve 30 and the retainer 45 have moved out sufficiently for the sleeve to have completely opened the cover 22, the end 42 of the circumferential spring 27 engages in the slot 40 in the shell 30 and arrests movement of the shell, the slot 40 being spaced sufficiently inwardly from the outer end of the shell that the shell has succeeded in raising the cap 22 to the full height thereof before the end 42 of the spring engages the slot.

45 At this point shown in Figs. 3 and 8, the shell 30 ceases its outward movement and the beads 52 contract within the interior of the shell to start the lipstick moving out of the shell 30. The pressure of the fingers 50 on the beads 52 expands the shell 30 into gripping engagement with the casing 15 so as to prevent further movement of the shell. This condition persists until such a time as the lipstick is entirely retracted within the shell 30 and the beads 53 have become positioned about the inner end of the shell 30. The button 57 50 at this point contacts the inner end of the slot 38 and pulls the shell 30 out of engagement with the end of the spring 42 and retracts the shell into the casing.

55 It will be noted that the sleeve 30 moves in advance of the lipstick 60 to open the cover 22 and that it maintains the cover open until the lipstick is entirely retracted within the sleeve 30, thus precluding the lipstick from coming in contact with the cover during its normal movement.

Having thus described the invention, it is realized that it is susceptible to various changes and modifications coming well within the scope of one skilled in the art and it is not, therefore, desired to limit the invention to the precise form herein shown and described, but only by the scope of the appended claims.

60 What is claimed as new and desired to secure by Letters Patent is:

1. In a device of the character described, a 10 casing, a cover mounted on said casing, means constantly urging said cover into closed position on said casing, a sleeve mounted for axial movement within said casing and adapted to open said cover and to retain said cover open 15 when said sleeve projects from said casing, a lipstick retainer within said sleeve and adapted for movement therewith, means to move said retainer and said sleeve simultaneously out of said casing whereby said sleeve opens said 20 cover, means to stop the movement of said sleeve while permitting continued outward movement of said retainer, and means retaining said sleeve in projected position, said retaining means being releasable when said retainer reaches a predetermined retracted position to permit the simultaneous withdrawal of both the sleeve and the retainer within said 25 casing whereby the cover closes under the influence of the first mentioned means. 30

2. In a device of the character described, a 35 casing, a cover for said casing, means constantly urging said cover into closed position on said casing, a sleeve mounted for movement within said casing and having an arcuate aperture 35 therein, said sleeve being adapted to open said cover upon movement of said sleeve out of said casing and to retain said cover open against the action of said means, a lipstick retainer mounted within said sleeve and adapted for 40 movement therewith, means to move said lipstick holder and said sleeve outwardly simultaneously, means engageable in said aperture to stop the movement of said sleeve while permitting the continued outward movement of 45 said retainer, means holding said sleeve in projected position during retraction of said lipstick retainer, said means being releasable upon said retainer reaching a predetermined position within said sleeve whereby continued retraction of the retainer causes simultaneous retraction of the sleeve. 50

3. In a device of the character described, a 55 casing, a cover for said casing, a circumferential spring mounted within said casing adjacent the top and forming a hinged connection between said cover and said casing, means constantly urging said cover into closed position on said casing, a sleeve mounted for axial movement in said casing and adapted upon being 60 projected from said casing to open said cover and retain said cover in open position, said sleeve having a circumferential aperture therein spaced from the outer end thereof, a lipstick 65 retainer mounted within said sleeve for movement therewith, means to move said sleeve and said retainer outwardly simultaneously, a stop member formed on an end of the circumferential spring and engageable with said aperture to arrest the movement of said sleeve, when 70 said sleeve has moved a sufficient distance out of said casing to completely open said cover, while permitting the continued outward movement of said retainer, means holding said sleeve in projected position, said means becoming in- 75

effective upon said retainer being retracted to a predetermined position in said sleeve whereby further retraction of the retainer into the sleeve causes simultaneous movement of both said retainer and said sleeve whereby said cover is closed by the action of said first named means.

5. In a device of the character described, a casing, a cover mounted on said casing, means constantly urging said cover into a closed position, an expansible sleeve mounted for axial movement within said casing and adapted upon expulsion of one end thereof from said casing to open said cover, a lipstick retainer mounted within said sleeve and adapted for movement therewith, a plurality of fingers on the inner end of said retainer, beads on the ends of said fingers engageable with the inner end of said sleeve to expel said sleeve from said container whereby said cover is opened, means to arrest 10 the outward movement of said sleeve whereby further movement of said retainer contracts the beads radially into said sleeve to expand the sleeve against the walls of said casing while permitting further outward movement of the retainer.

15. In a device of the character described, a casing, a cover for said casing, means constantly urging said cover into closed position on said casing, a sleeve mounted for axial movement 20 in said casing and having a circumferential aperture therein spaced inwardly from the outer edge of said sleeve, a lipstick retainer mounted within said sleeve, a plurality of axially extending fingers on said retainer, beads formed at the 25 ends of each of said fingers engageable with

the inner end of said sleeve to actuate said sleeve from said retainer, means to cause movement of said retainer whereby said retainer and said sleeve move outwardly together, means engageable in said aperture to stop the movement 5 of said sleeve when said sleeve has moved to a position fully opening said cover, means to hold said sleeve in projected position during a portion of the retraction of said retainer and releasable to permit the simultaneous retraction of 10 both the sleeve and the retainer when said retainer reaches a predetermined point in its retraction.

20. In a device of the character described, a casing open at one end and having an elongated slot, hinged cover means at the open end of the casing, a member mounted for longitudinal sliding movement in said casing and having an elongated slot, a retainer for a cosmetic stick longitudinally slidably mounted within the member, an actuating button having a part projecting through the elongated slots in the casing and member and engaging the retainer so that longitudinal shifting of the button slides the retainer longitudinally of the casing, means for 25 imparting movement of the button and retainer to the member so that the member is projectable from the open end of the casing simultaneously with outward longitudinal movement of the retainer, outward projection of the member from the casing opening the hinged cover means, and means to cause the cover means to follow the member to a closed position upon retraction of the member.
